GEORGE H. CRAWFORD, INVENTOR.
Rickey, Blough & Nales
BY

HIS ATTORNEYS.

UNITED STATES PATENT OFFICE.

GEORGE H. CRAWFORD, OF LORAIN, OHIO.

DISPLAY FIXTURE.

1,405,569.

Specification of Letters Patent.

Patented Feb. 7, 1922.

Application filed January 31, 1921. Serial No. 441,140.

To all whom it may concern:

Be it known that I, GEORGE H. CRAWFORD, a citizen of the United States, residing at Lorain, in the county of Lorain and State of Ohio, have invented a certain new and useful Improvement in Display Fixtures; and I do hereby declare the following to be a full, clear, concise, and exact description of the invention, such as will enable others skilled in the art to which it appertains to make and use the same.

My invention relates to improvements in display fixtures for shirts or other like merchandise, such as pajamas, sweaters, and the like.

An object of this invention is to improve the face of display fixtures of the type above mentioned, whereby certain advantages are gained which have heretofore been absent in inventions of this class.

A further object of the invention is to provide an improved display stand whereby the merchandise adapted to be displayed may be exhibited in various positions.

Another object of the invention is to provide a stand of this nature, which is more substantial, inexpensive to manufacture, and which when in operation presents a pleasing appearance to the eye of the observer.

Another object of my invention is to provide a display board for the said display fixture having a portion of its surface composed of a yielding material, such as cork, provided in the form of pads, which are integrally secured in right and left corners of the board, so that the window-trimmer or other operator may affix the article to be displayed to the said board by pins or other like securing means, and which pins are pro-

jected into the cork pads with a minimum of effort. I find that cork is particularly suitable for this purpose, since it is of the required softness, and when the pins are removed, the cork is sufficiently resilient to close the holes into which the pins had been projected, so that a smooth surface is maintained. Also, since these pins can be inserted and withdrawn with a minimum of effort, the danger of injuring delicate fabrics and the like which may be attached to the board is minimized.

Other objects of my invention and the invention itself will become apparent to those skilled in the art by reference to the draw-

ing which accompanies this specification, 55 and in which drawing—

Fig. 1 is a front view of an embodiment of my invention in the form of an improved shirt display fixture.

Fig. 2 is a view of the fixture of Fig. 1 60 taken from a side angle to the view of Fig. 1, on a reduced scale.

Fig. 3 shows the shirt display fixture adjusted with its display board in a different 65 angular position.

Fig. 4 shows the display board in still another position.

Fig. 5 shows the display board in still another position.

Fig. 6 shows a rear view of the display 70 board, the stand supporting means being omitted.

Fig. 7 shows a method of securing the cork pads in position within the display board.

Fig. 8 illustrates a front view of the display board with holes to insert steel wire, whereby the pads may be secured to the 75 board.

Fig. 9 is a side view of the supporting lug 80 which is adapted to be attached to the rear of a display board. In this figure a plurality of openings, any of which are adapted to receive the neck of the pedestal to adjust the display board to different angular positions, is shown.

Fig. 10 shows a rear view of the supporting lug of Fig. 9.

Fig. 11 shows a side view of the display board with the different positions which the pedestal may take with reference to the display board, depending on the connection made.

Referring now to the drawings, in all of which like parts are designated by like reference characters, it will be seen that at 95 2 I show a display board having a pair of cork pads inserted at C and C', the said cork pads being inserted in the display board in openings provided for the purpose, the said openings passing all the way through the board and the cork pads in the form of circular wafers, being pressed into the said openings. By so constructing the cork pads, I am enabled to replace them after they become broken or worn from use, and at the 100 same time I am also enabled to make a display board composed principally of wood and having the cork inserts of minimum 105

area placed just at the proper points where they will be needed only to attach merchandise, such as shirts. To the rear of the board 2, at 3 I show a strip, which preferably is made of wood, which is secured by screws or nails 4 to the board, and to this strip 3 is rigidly affixed the lug W. The position of the lug W, although hidden in some of the figures, is indicated by the line leading from the reference character W in the different figures.

The lug W is preferably semi-spheroidal or semi-egg shaped. In the embodiment illustrated I have shown the preferred form 15 of my invention, wherein the lug is nearly semi-egg shaped, except that one of the ends I make much blunter than the other. This is for adjustment purposes, as will be later described.

20 In the lug W I have provided a plurality of drilled holes A, B, C, D and E, these preferably being drilled at right angles to the surface of the lug whereat they are drilled, and by suitably positioning the said holes 25 at a plurality of separated points on the surface of this lug, I am enabled to get widely varying adjustment results. However, in the case of the holes D and E, I purposely drill the hole D at an angle less 30 than a right angle to the surface whereat it is drilled, so as to differentiate the angular position of the board when the neck of the pedestal is inserted into the hole D from the position it would assume when inserted 35 into the hole E. In this way, as shown in Figs. 1, 2, 3, 4, and 5, and as illustrated in the diagram of Fig. 11, the pedestal stand and the board assume different angular positions relative to each other, depending 40 upon which hole the pedestal stand neck is inserted, so that the merchandise to be displayed, as in a store window, can be displayed at various angles, depending upon the effect desired to be produced upon the 45 eye of the observer, and which effect depends somewhat upon the environment of the stand or its position within the window.

I may insert the cork pads C merely by fitting them tightly in the openings provided 50 in the board 2, but I have provided a reinforcing means, comprising crossed steel wires F and H, as illustrated in Figs. 7 and 8, which pass through the body of the cork, the cork being preferably molded over the said wires, and the wires are anchored in holes i (see Fig. 8) or any other suitable manner. This reinforces the positioning of

the cork pads within the board, so that they may not readily be displaced. The area 60 taken by the wires is negligible, and being round, a pin meeting them will be deflected and the wires will not interfere with the placing of a pin through the cork.

Having thus described my invention, I 65 wish it to be understood that while I have illustrated the same in connection with a particular embodiment, that it is by no means limited to the same, but is capable of being embodied in other structures differ- 70 ent from that shown.

What I claim as my invention is:

1. In a display fixture, a pedestal comprising a base portion, an upright supporting stem secured at one end to the base portion, a display board, a lug adapted to be affixed to the rear of the display board, said lug being substantially semi-spheroidal and having its flat face in contact with the rear face of the display board and secured there- 75 to, said lug presenting a plurality of sockets over its curved surface, said sockets being drilled substantially at right angles to the surface of the lug whereat they are drilled and having at least one hole drilled at an 80 angle to such a direction, said stem being adapted to be secured at its upper end within any desired one of the said sockets, said display board having a plurality of countersunk cork pad circular wafers disposed 85 within its face, securing means to secure the said wafers to the said board whereby the said board may be adjusted at various angles to the supporting stem, and whereby 90 merchandise may be pinned to the cork wafers to display the same. 95

2. In a display board, the combination with a pedestal, of a display board member, means whereby the said pedestal and the said display board may be attached at the upper end of the said pedestal, a pair of openings extending through the said display board at opposite corners thereof, the area of the said openings being relatively small compared with the area of the said board, cork pad circular wafers adapted to be inserted within the said openings, with the edge of the said wafers in intimate contact with the inside edges of the said openings, reinforcing wires embedded in the said cork 100 wafers, and means to attach the said wires to the said board outside the said board openings. 105

In witness whereof I have hereunto signed my name this 3rd day of December, 1920.

GEORGE H. CRAWFORD.
